UNITED STATES PATENT OFFICE

150,768

DESIGN FOR A DRESS

Lucy Hoshafian, New York, N. Y.

Application November 28, 1947, Serial No. 142,838

Term of patent 7 years

(CL. D3—26)

To all whom it may concern:

Be it known that I, Lucy Hoshafian, a citizen of the United States of America, residing in New York, county of New York, and State of New York, have invented a new, original, and ornamental Design for a Dress, of which the following is a specification, reference being had to the accompanying drawing, forming part thereof.

Fig. 1, is a front view of a dress showing my new design.

Fig. 2, is a rear view thereof.

I claim:

The ornamental design for a dress, substantially as shown.

LUCY HOSHAZIAN.
